(Cl. D54—2)

FIG.1

FIG.2

FIG.3

Figure 1 is a side elevational view of a trellis showing my new design, the center being broken away to indicate indeterminate length.

Figure 2 is a fragmentary view in perspective of the trellis shown in Figure 1.

Figure 3 is a fragmentary view in perspective, greatly enlarged, taken on line 3—3 in Figure 1.

I claim:

The ornamental design for a trellis, substantially as shown.
